CLAIM

The ornamental design for sole for footwear, as shown and described.

DESCRIPTION

FIG. 1 is a front perspective view of a sole for footwear showing my new design;

FIG. 2 is a front view thereof;

FIG. 3 is a back view thereof;

FIG. 4 is a right side view thereof;

FIG. 5 is a left side view thereof; and,

FIG. 6 is a bottom view thereof.

The broken lines in the drawings illustrate environment that form no part of the claimed design.

The shading in the drawings does not reflect any particular surface colors. Color forms no part of the claimed design.
